US00D767380S

(12) **United States Design Patent** (10) Patent No.: **US D767,380 S**
(45) Date of Patent: ** Sep. 27, 2016

(54) **PACKAGING CASTORS**

(71) Applicant: **LIBERTY HARDWARE MFG. CORP.**, Winston-Salem, NC (US)
(72) Inventors: **James Allen Austin, III**, High Point, NC (US); **Earl David Forrest**, Asheboro, NC (US); **Nathaniel Faltin Dutton Schultz**, Charlotte, NC (US); **Christine Lemnios**, Greensboro, NC (US); **Yinghong Zhang**, Guangzhou (CN); **Jeanie Matherly**, Oak Ridge, NC (US); **Matthew Klein**, Apex, NC (US); **Patrick William Boehnen**, Summerfield, NC (US); **Laura Hawkins**, Madison, NC (US)

(73) Assignee: **LIBERTY HARDWARE MFG. CORP.**, Winston-Salem, NC (US)

(**) Term: **14 Years**

(21) Appl. No.: **29/480,730**

(22) Filed: **Jan. 29, 2014**

(51) LOC (10) Cl. **08-05**

(52) U.S. Cl.

USPC **D8/375**

CLAIM

The ornamental design for packaging castors, as shown and described.

DESCRIPTION

FIG. 1 is a front side view of packaging castors according to the present design;

FIG. 2 is a rear side view thereof;

FIG. 3 is a left side view thereof;

FIG. 4 is a right side view thereof;

FIG. 5 is a top view thereof; and,

FIG. 6 is a bottom view thereof.

The broken lines shown represent unclaimed subject matter and form no part of the claimed design.
